UNITED STATES PATENT OFFICE.

GEORGE E. PRENTICE, OF NEW BRITAIN, CONNECTICUT, ASSIGNOR TO
THE TRAUT & HINE MANUFACTURING COMPANY, OF NEW BRITAIN,
CONNECTICUT, A CORPORATION OF CONNECTICUT.

CLASP FOR GARMENT-SUPPORTERS.

No. 840,515.

Specification of Letters Patent.

Patented Jan. 8, 1907.

Application filed October 1, 1904. Serial No. 226,828.

To all whom it may concern:

Be it known that I, GEORGE E. PRENTICE, a citizen of the United States, residing at New Britain, in the county of Hartford and State of Connecticut, have invented certain new and useful Improvements in Clasps for Garment-Supporters; and I do hereby declare the following to be a full, clear, and exact description of the same, reference being had to the accompanying drawings, forming a part of this specification, and to the letters of reference marked thereon.

This invention relates to clasps for garment-supporters, and particularly to that class of clasps adapted to directly engage the garment itself and serve as the means for connecting the garment with the supporter.

The objects of the invention are to provide a simple and strong device adapted to effect a positive engagement with a garment of either thick or thin fabric and to so cushion and distribute the strain thereon as to prevent tearing or other injury to the fabric.

The invention consists in certain novel details of construction and combinations and arrangements of parts, all as will be now described, and pointed out particularly in the appended claims.

Referring to the accompanying drawings, Figure 1 is a front elevation of a clasp embodying the present improvements in its closed or locked position. Fig. 2 is a side elevation of the same. Fig. 3 is a perspective view with the tongue partially opened in full lines and full open in dotted lines. Figs. 4 and 5 are details of the elastic cushion detached from the clasp. Fig. 6 is a detail view of a modified form of cushion. Fig. 7 is an elevation of the operating arm or lever.

Like letters of reference in the several figures indicate the same parts.

The body of the clasp (indicated by the letter A) is preferably made of sheet metal, and at its lower end there is an abutment D, formed, preferably, by bending up the lower end of the body A. The upturned end is preferably turned back over the body portion A, whereby a recess or chamber is formed for the reception of an elastic cushion B, in which instance the upturned end and elastic cushion constitute the abutment. An operating arm or lever C is pivotally connected at an intermediate point with the upper end

of the body, one end of said lever C serving both as a convenient finger-piece and as the means for securing the clasp to the supporter, while the opposite end is pivotally connected with the upper end of the locking-tongue D.

The tongue D is preferably formed of sheet metal, while the operating arm or lever is of wire bent into the form of a loop c, through which the supporter-web may pass and to the lower bar of which the body is pivotally connected by ears a a, bent forward of the plane of the body and around the lower bar of the loop, as shown. The ends of the wire approach closely together or meet at the center of the lower bar of the loop and are then bent outwardly in opposite directions to form pintles c' c' for ears d d, forming the pivotal connections between the lever and tongue.

The end of the tongue is adapted to seat by an end wire thrust against the cushion held by the body and to form, with the locking-lever, a toggle, the joint of which moves across the dead-center to retain the device in its locked position, as is well understood; but it will be noted that in the present structure the desired result is secured by the simple expedient of turning the ears on the body forwardly and those on the tongue backwardly. This formation not only makes the device thin but affords ample space between the body and tongue for the edge of the garment when the clasp is locked.

The supporter being attached to the operating-lever above its axis tends to hold the parts in locked position when under strain, and this effect is somewhat increased by setting the upper portion of the operating-lever back at a slight angle to the lower end and plane of the clasp when in closed position, as will be readily understood from an inspection of Fig. 2.

The cushion before referred to is preferably soft rubber and preferably has a cavity or recess, such as b or b', Figs. 4 and 6, to increase its range of elasticity. It is held in place in the hook-shaped end of the body by clamping the latter upon it or by the teeth or spurs i, the ends of which may be seated in the rubber on each side of the central projection h, behind which the cushion is confined. A lip b' of the cushion preferably projects for-

wardly to prevent contact of the garment with the metal of the body and to afford a smooth elastic surface for that part of the garment subjected to the greatest strain, 5 while an apron or flange b^2 projects up at the inner side to form a stop against which the garment and tongue may be pressed in closing the device. This apron also performs the important function of preventing the garment from being pushed down behind the cushion by the tongue and insures it being pressed only against a soft resilient body.

It will be noted that when the clasp is in closed position the tongue will be forced into 15 the elastic cushion, as shown in Fig. 2, and through the resiliency of the cushion the device will clasp and hold securely either thick or thin fabrics without danger of tearing them.

20 The recesses or cavities in the cushion increase the elasticity to a very material extent, and at the same time the resistance of the cushion is sufficient to secure a firm grip under any conditions.

25 Having thus described my invention, what I claim as new, and desire to secure by Letters Patent, is—

1. A clasp for garment-supporters embodying a body portion having one end turned back to form a chamber, an elastic cushion held in said chamber, a tongue, a locking-lever formed of a single piece of wire formed into an upper webbing-loop to the lower bar of which the upper end of the body portion is 30 pivotally connected, said loop constituting the means for operating the lever, the ends of the wire being bent outwardly from the center of said lower bar, to which wire ends the upper end of the tongue is pivotally connect- 35 ed; substantially as described.

40 2. A clasp for garment-supporters, em-

bodying a body portion having an upturned end and elastic cushion constituting an abutment, a tongue, an operating arm or lever, pivotally connected at an intermediate point 45 with the upper end of the body, the upper end of said lever constituting the means for securing the clasp to the webbing and for operating the lever, the lower end of the lever being pivotally connected with the upper end 50 of the tongue; substantially as described.

3. A clasp for garment-supporters embodying a sheet-metal body having one end turned back to support the thrust of a locking-tongue and ears at the opposite end, a sheet-metal locking-tongue having ears at one end and a wire locking-lever formed into an upper webbing-loop, the lower bar of which is pivotally connected with the upper end of the body by the ears bent forward of the 60 plane of the body, the ends of the wire being bent outwardly from the center of said lower bar and pivotally connected with the upper end of the tongue by the ears bent backwardly of the plane of the tongue; substan- 65 tially as described.

4. A clasp for garment-supporters embodying a body portion having one end turned back to form a chamber, an elastic cushion held in said chamber having a forwardly-extending lip and an apron or flange, projecting up at the inner side, a tongue, a lever pivotally connecting one end of the tongue and one end of the body portion to form a toggle, whereby the cushion receives the end of the 70 tongue when the clasp is closed; substan- 75 tially as described.
